UNITED STATES PATENT OFFICE.

ALFRED J. SODEN, OF NEWARK, NEW JERSEY, ASSIGNEE TO CRUCIBLE STEEL COMPANY OF AMERICA, OF PITTSBURGH, PENNSYLVANIA.

ARMOR-PIERCING PROJECTILE.

1,095,173.

Specification of Letters Patent.

Patented Apr. 28, 1914.

Application filed January 7, 1913. Serial No. 740,742.

To all whom it may concern:

Be it known that I, ALFRED J. SODEN, a citizen of the United States, residing at Newark, in the county of Essex and State of New Jersey, have invented certain new and useful Improvements in Armor-Piercing Projectiles, of which the following is a specification.

My invention relates to improvements in armor-piercing projectiles, and it consists in the constructions, combinations and arrangements herein described and claimed.

An object of my invention is to provide an improved armor-piercing projectile, constructed to present a maximum resistance throughout to the compression and shearing strains incident to impact, and to decrease the velocity and energy required for penetration.

A further object of my invention is to provide an improved armor-piercing projectile which will efficiently bite into the armor-piercing plate at large angles of incidence, and in which failure of the projectile through a whipping action and crushing and shearing strains will be minimized under all conditions of impact.

In the accompanying drawings, forming a part of this application and in which similar reference symbols indicate corresponding parts in the several views: Figure 1 is an axial section, illustrating one embodiment of my invention applied to a 13-inch projectile; Fig. 2 is a fragmentary section, illustrating a preferred manner of notching the base of the band score; Fig. 3 is a diagrammatical view, showing the form of the axial elements of the contour of the projectile point, and Fig. 4 is a diagrammatical view, drawn to scale, showing the variable curve comprising the tip portion of said axial elements.

Referring to the drawings, 1 indicates the cylindrical body portion of a projectile provided with my preferred point 2, which is shown of less length than the standard ogival point having a uniform curvature radius of two calibers. The projectile is provided with a band 3, and a base plug 4 constructed to screw tightly to place against a suitable gasket.

In my improved projectile, the point comprises a base portion 5 having a fixed radius of longitudinal curvature of approximately three calibers, and preferably slightly less; 55 said base portion having a length substantially equal to .85 caliber. The point is formed with a tip portion having a length of substantially .48 caliber; all axial elements of the tip's contour comprising a variable 60 curve blunter than the curvature of a standard naval ogival point having a uniform curvature radius of two calibers. This improved construction provides a projectile having a point of less length than a standard ogival 65 point having a uniform curvature radius of two calibers, which is sharper throughout its base portion and blunter at substantially .48 caliber from the tip; the point becoming blunter at the cross-section where said point 70 is approximately three-fourths caliber in diameter. The radius of curvature of the nose of the projectile decreases progressively from approximately three calibers at .48 caliber from the tip to approximately 1 $\frac{1}{2}$ 75 calibers immediately adjacent the tip.

From the above description, it will be understood that my invention provides an improved projectile, having a point substantially one and one-third calibers in 80 length; all axial elements of the point comprising a base arc extending through less than two-thirds the length of the point, and a variable curve forming a tip portion 85 blunter than that of a standard ogival point having a uniform radius curvature of two calibers. This provides an improved projectile capable of efficiently biting into an armor plate even at large angles of incidence, and requiring a decreased velocity 90 and energy for penetration. The improved point minimizes danger of crushing and chipping of the tip, and provides a maximum resistance to failure of the projectile by the shearing and compression strains incident to impact. 95

Having thus described my invention, what I claim as new and desire to secure by Letters-Patent is:

An improved armor-piercing projectile 100 provided with a nose having an ogival point with a radius adjacent to its tip of approxi-

mately $1\frac{1}{2}$ calibers, said radius increasing progressively to approximately 3 calibers at a length of approximately .48 caliber from said tip, and then having a fixed curvature with a radius of approximately 3 calibers for a length of approximately 1 caliber, substantially as described.

In testimony whereof I affix my signature in presence of two witnesses.

ALFRED J. SODEN.

Witnesses:

Wm. H. CAMFIELD,
M. A. JOHNSON.
